UNITED STATES PATENT OFFICE.

WILLIAM A. INMAN, OF HARTFORD CITY, INDIANA.

CATTLE-GUARD.

1,210,806.

Specification of Letters Patent.

Patented Jan. 2, 1917.

Application filed August 9, 1916. Serial No. 114,019.

To all whom it may concern:

Be it known that I, WILLIAM A. INMAN, a citizen of the United States, residing at Hartford City, in the county of Blackford and State of Indiana, have invented certain new and useful Improvements in Cattle-Guards, of which the following is a specification.

This invention relates to an improved cattle guard for use in connection with rail-ways and the principal object of the invention is to provide a cattle guard which is so constructed that it may be connected with the ties and loosely connected therewith so that it may be easily disconnected and to further permit the ties to have a certain amount of movement without the guard moving with the ties.

Another object of the invention is to so construct this guard that the tread plates may be bodily disconnected from the base.

Another object of the invention is to so construct this guard that it will normally remain in an elevated position, the guard being depressed when cattle step upon it and returning to the elevated position when the cattle step back off of the guard.

This invention is illustrated in the accompanying drawings, wherein:

Figure 1 is a top plan view of the improved guard. Fig. 2 is a longitudinal sectional view through the cattle guard taken along the line 2—2 of Fig. 1. Fig. 3 is a vertical transverse sectional view taken along the lines 3—3 of Fig. 1. Fig. 4 is an enlarged fragmentary sectional view taken along the line 4—4 of Fig. 3.

This cattle guard will be supported upon the ties 10 which carry the rails 11 and will extend between the rails and also outside the rails. The side strips or supporting strips 12 are secured to the ties 10 by means of fasteners which pass through longitudinally extending slots formed in the ends of these side strips and it will thus be seen that the guard will be permitted of sliding movement longitudinally of the track thus permitting independent movement of the ties and guard. These side bars carry cross bars 14 which are formed of angle iron and have their upstanding flanges provided with slots to receive the hooked ends of the platform strips 15. These platform strips have their upper ends extending in overlapping relation and are provided with openings through which extends the rod 16 serving to pivot-

ally connect the platform strips and thus permit the platform to move longitudinally when depressed. Tread plates 17 are carried by these strips 15 and between the platform strips engage the supporting plates 18 which plates rest upon the side strips 12 at their outer ends as shown in Fig. 3.

Beneath the inner ends of the platform there has been provided a cross strut or housing 19 which housing has its end portions secured to the outer side strips 12 and is provided with openings through which extend the reduced ends of the posts 20. These posts 20 are provided at their upper end with yokes to engage the rods 16 and are provided at their lower ends with abutment nuts 21 serving to limit the extent to which the springs 22 may move the posts upwardly. A regulating bar extends beneath the cross tie or housing 19 and is provided with key hole openings through which the bolts 20 pass, the openings at the larger ends of the key hole openings being of such size as to permit the securing nuts 21 to pass through the bar. This bar is slidably mounted by means of fasteners 24 and it will thus be seen that when it is desired to have the rods and platforms raised above the height shown in Fig. 3, this bar can be moved longitudinally and the bolts may then move upwardly to such an extent that the rods will be positioned above the height of the treads of the rails. The rods can then be drawn longitudinally and thus the strips 15 will be disconnected. By withdrawing the fasteners 18 the platform can then be readily disconnected from the ties. A shoe or supplemental housing 25 is positioned beneath the housing 19 and secured thereto by means of bolts 26 and will thus provide room to permit the posts 20 to move downwardly when pressure is applied to the platform.

When in use the cattle guard will be mounted as shown in Fig. 1. If cattle attempt to walk upon the tracks, they must first step upon the platform at either end of the guard and in doing so, the weight will cause the platform upon which the animal steps to drop. The dropping of the platform will alarm the animal and it will step off of the platform which will then immediately return to the original position under the action of the springs 22. From an inspection of Fig. 3, it will be readily seen that this guard does not extend above the

rails and that therefore it will not interfere with the trains moving along the track. Therefore this device will be so constructed that it will be out of the way and at the same time will be so constructed that it will oscillate very easily to prevent cattle from walking upon the track and will return to the original position when weight is removed from the platform.

10. What is claimed is:—

1. A cattle guard comprising side strips adapted for connection with the cross ties of a track, a housing secured beneath said side strips and extending transversely of the track at a point intermediate the length of the side strips, cross bars secured upon said side strips and provided with upstanding flanges having openings formed therein, tread platforms including longitudinally extending bars having their outer end portions hooked and extending through the openings of said flanges to slidably connect the platform with the cross bars, a pivot rod extending through the inner end portions of the longitudinally extending bars of said platform, supporting posts positioned in said housing and having reduced threaded lower end portions extending through openings in the bottom of the housing and provided at their upper ends with yokes engaging said pivot rod, springs positioned upon the reduced ends of said posts to yieldably hold the posts in a raised position, securing nuts screwed upon the threaded lower ends of said posts, and an abutment bar slidably connected with said housing and provided with key-hole openings through which said posts pass.

2. A cattle guard comprising side supporting strips adapted for sliding connection with the cross ties of a railway track, cross bars carried by said side strips and having upstanding perforated flanges, platforms including longitudinally extending bars having their outer end portions passing through the slots to slidably mount the outer ends of the platforms, a pivot rod pivotally connecting the inner end portions of the bars of said platforms, a housing extending beneath said pivot rod, posts slidably carried by said housing and engaging said pivot rods, and resilient means carried by said posts for yieldably holding the same in a raised position.

3. A cattle guard comprising side strips, cross bars connected with the end portions of said side strips, a housing extending beneath the side strips and secured thereto, an adjusting bar slidably mounted beneath said housing and provided with key-hole open-

ings, posts slidably passing through said housing and through the key hole openings of said adjusting bar and provided with securing nuts forming abutments engaging said bar, resilient means yieldably holding said posts in a raised position, platforms including longitudinally extending bars having their outer end portions slidably connected with said cross bars and having their inner end portions extending in overlapping relation, and a pivot rod passing through the overlapping inner end portions of the bars of said platforms and engaged by said posts.

4. A cattle guard comprising platforms including longitudinally extending bars having their inner end portions extending in overlapping relation, a pivot rod extending through the overlapping inner end portions of said longitudinally extending bars, tread plates for the platforms carried by said longitudinally extending bars and providing gutters between the bars, and a supporting structure for said platform including cross bars slidably engaged by the outer ends of the longitudinally extending bars of said platforms, posts engaging said pivot rod, and springs yieldably holding the posts in a raised position.

5. A cattle guard including platforms, a pivot rod pivotally connecting the inner end portions of said platforms, and a supporting structure for said platforms including cross bars for slidably engaging the outer end portions of said platforms, a housing forming part of said supporting structure and extending beneath said pivot rod, posts carried by said housing and engaging said pivot rod and yieldably held in a raised position, and a hood connected with and extending beneath said housing.

6. A cattle guard including a supporting structure having side bars adapted for connection with the ties of a track to permit longitudinal movement of the supporting structure upon the ties, a housing carried by said side bars, end bars carried by said side bars, platforms slidably and pivotally connected with the end bars, a pivot rod pivotally connecting the inner end portions of said platforms, and supporting posts slidably carried by said housing and engaging said pivot rod and yieldably held in a raised position.

In testimony whereof I affix my signature in presence of two witnesses.

WILLIAM A. INMAN.
